UNITED STATES PATENT OFFICE.

WILLIAM G. TROHON, OF EAST DANVERS, MASSACHUSETTS, ASSIGNOR TO UNITED SHOE MACHINERY CORPORATION, OF PATERSON, NEW JERSEY, A CORPORATION OF NEW JERSEY.

BOBBIN-CASE-RETAINING DEVICE.

Application filed June 26, 1919. Serial No. 306,913.

To all whom it may concern:

Be it known that I, WILLIAM G. TROHON, a citizen of the United States, residing at East Danvers, in the county of Essex and 5 State of Massachusetts, have invented certain new and useful Improvements in Bobbin-Case-Retaining Devices; and I do hereby declare the following to be a full, clear, and exact description of the invention, such as will enable others skilled in 10 the art to which it appertains to make and use the same.

The present invention relates to bobbin case retaining devices for sewing machines 15 and more particularly to such devices for sewing machines of the type in which the bobbin case is mounted in a recess in a rotary oscillating shuttle located at the front of the machine.

20 In this type of sewing machine as commonly constructed, the bobbin case is retained in the recess in the shuttle and is prevented from oscillating with the shuttle by means of a retainer having a recess to 25 receive the nose of the bobbin case. This retainer is mounted upon a pivoted support and in certain sewing machines of this type, such as the one illustrated and described in 30 the application for United States Letters Patent of Thomas H. Seeley, Serial No. 122,002, filed Sept. 25, 1916, the pivoted support constitutes the cover or door of a heat 35 retaining and protective casing or hood. In the operation of these machines, wax 40 accumulated from the waxed thread frequently causes the bobbin case to adhere more or less to the bobbin case retainer so that when the retainer is retracted by means of the pivoted support to permit access to 45 the bobbin or other parts of the machine, the bobbin and bobbin case frequently fall on the floor and the thread becomes un- 50 wound. As these parts are quite hot, particularly when a heat retaining hood is em- 55 ployed, it is very inconvenient for the operator to handle and replace them in the machine.

Accordingly, one of the objects of the present invention is to provide novel and 55 improved means for preventing displacement of the bobbin and bobbin case during the retraction of the bobbin case retainer.

With this object in view, one of the features of the present invention contemplates

the provision in a sewing machine having 55 a shuttle and a bobbin case mounted for relative rotary movement and a bobbin case retainer capable of being retracted therefrom, of means comprising a member adjacent a side of the bobbin case for preventing 60 displacement of the bobbin case during the retraction of said retainer and capable of being moved to permit the bobbin case to be removed and replaced. In the present embodiment of the invention said member 65 consists of a spring arm extending across a side of the bobbin case and capable of being retracted therefrom by means of a handle forming an extension of said arm, although the broader features of the invention 70 are not limited to this specific construction.

The several features of the present invention will be clearly understood from the following description and accompanying drawings in which:—

Figure 1 is a front elevation of a portion of a sewing machine embodying the features of the invention in their preferred form; Fig. 2 is a plan view, partly in section, of 80 the portion of the machine illustrated in Fig. 1; and Fig. 3 is a detailed perspective view of the improved device.

The machine as illustrated in the drawings may be and preferably is the same as 85 the machine illustrated and described in the application for Letters Patent of Thomas H. Seeley, hereinbefore referred to and, accordingly, only so much of the machine is described herein as is necessary for an 90 understanding of the present invention. This machine is provided with a loop taker in the form of a shuttle 10 which is rotatably oscillated in a shuttle race 12 at the front of the machine. The shuttle race 95 constitutes a part of a casing 14 having a lug 16 which is secured by a bolt 18 to a lug 20 on the frame of the machine. The bobbin or locking thread is contained in a bobbin case 22 which is removably inserted 100 in a recess in the front of the shuttle. The bobbin case is retained in the recess of the shuttle and is prevented from oscillating with the shuttle by means of a retainer 24, provided with a recess 26 to receive a nose 105 28 on the bobbin case. The retainer 24 is mounted upon a movable support 30 which, in the present instance, constitutes the cover

of a heat retaining casing or hood for the upper part of the machine as fully illustrated and described in said application.

The improved device as illustrated in the drawings, is formed from a piece of resilient wire which is bent to provide a curved substantially horizontal arm 32, a downwardly and outwardly inclined handle 36, a vertical coil 38, a horizontal coil 40, and a downwardly projecting end portion 42. The bolt 18 and lugs 16 and 20 are conveniently utilized to secure the improved device in position, the bolt being inserted through the horizontal coil 40 with the coil located between the head of the bolt and the lug 20, and the downwardly projecting end portion 42 engaging the rear side of the lug 16 to prevent the device from turning laterally. The arm 32 is suitably bent to clear the casing 14 and the free end of the arm is turned forwardly and is spaced slightly from the bobbin case in order not to interfere with the bobbin thread in passing across the bobbin case.

With this construction, it will be seen that upon opening the door 30 the arm 32 will yieldingly strip the bobbin case from the retainer on the door and retain the bobbin case in the recess in the shuttle.

The arm 32 may be moved upwardly across the bobbin case, to permit removal and replacement of the bobbin case, by means of the handle 36, the coil 38 which is interposed between the handle and the stationary portion of the device permitting the arm to be thus moved with only a comparatively slight application of pressure on the handle.

The nature and scope of the present invention having been indicated and a machine embodying the several features of the invention in their preferred form having been specifically described, what is claimed is:—

1. A sewing machine having, in combination, a shuttle and a bobbin case mounted for relative rotary movement, a retainer for the bobbin case capable of being retracted therefrom, and means for preventing displacement of the bobbin case during the retraction of said retainer comprising a spring arm extending across a side of the bobbin case.

2. A sewing machine having, in combination, a shuttle and a bobbin case mounted for relative rotary movement, a retainer for

holding the bobbin case in the shuttle capable of being retracted therefrom, and means for preventing displacement of the bobbin case during the retraction of said retainer, and capable of being moved to permit the removal of the bobbin case comprising an arm extending across a side of the bobbin case.

3. A sewing machine having, in combination, a shuttle and a bobbin case mounted for relative rotary movement, a retainer for the bobbin case capable of being retracted therefrom, means comprising a spring arm extending across a side of the bobbin case for preventing displacement of the bobbin case during the retraction of said retainer, and an extension of the spring arm constituting a handle for moving the spring arm to permit the removal of the bobbin case.

4. A sewing machine having, in combination, a shuttle and a bobbin case mounted for relative rotary movement, a retainer for the bobbin case capable of being retracted therefrom, and means comprising a member adjacent a side of the bobbin case to engage and prevent displacement of the bobbin case during the retraction of said retainer.

5. A sewing machine having, in combination, a shuttle and a bobbin case mounted for relative rotary movement, a retainer for holding the bobbin case in the shuttle capable of being retracted therefrom, and a spring arm mounted independently of said retainer and extending across a side of the bobbin case for preventing displacement of the bobbin case during the retraction of said retainer.

6. A sewing machine having, in combination, a shuttle and a bobbin case mounted for relative rotary movement, a retainer for the bobbin case capable of being retracted therefrom, and means for preventing displacement of the bobbin case during the retraction of said retainer, said means capable of being retracted to permit removal of the bobbin case.

7. A sewing machine having, in combination, a shuttle and a bobbin case mounted for relative rotary movement, a retainer for the bobbin case capable of being retracted therefrom, and means arranged adjacent the retainer for preventing displacement of the bobbin case.

WILLIAM G. TROHON.
